DISPLAY STAND FOR WROUGHT IRON RAILING

Edward J. Kusel, 2343 Ridgewood Road, Akron, Ohio

Filed Nov. 30, 1961, Ser. No. 67,754

Term of patent 14 years

(Cl. D80—9)

FIG. 1

FIG. 2

FIG. 3

FIG. 4

FIGURE 1 is a front perspective view taken from the top and one side of a display stand for wrought iron railing.

FIGURE 2 is a top plan view thereof.

FIGURE 3 is a front elevational view thereof.

FIGURE 4 is a side elevational view thereof taken from the right of FIGURE 3.

The broken line representation of railings in FIGURE 1 is for purposes of illustration only.

I claim:

The ornamental design for a display stand for wrought iron railing, as shown and described.
